UNITED STATES PATENT OFFICE.

SAMUEL CHARLES YOUNG, OF ST. JOSEPH, LOUISIANA.

CARBURETOR LOCK.

Application filed June 5, 1926. Serial No. 114,039.

This invention relates to a lock for a carburetor, the general object of the invention being to provide means for preventing the throttle valve from being opened beyond a certain extent so as to prevent speeding of a vehicle.

Another object of the invention is to so form the lock that it can be held in position by the bolts which fasten the carburetor to the inlet manifold, the device being provided with means for preventing removal of some of such bolts when the device is in locked position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a perspective view of a carburetor and portion of the inlet manifold, showing the lock in position.

Figure 2 is an end view looking into the carburetor and showing the device in locked position.

Figure 3 is a perspective view of the device with the parts in open position.

As shown in these views, the device comprises a base or body 1 which is provided with the depending perforated ears 2 and the post 3 adjacent one end and the keeper member 4 at the other end, said member being provided with the keeper openings 5. An arm 6 is hingedly connected to the post 3 by the links 7 and said arm is provided with a channel-shaped head 8 which will receive the member 4 when the arm is swung downwardly into closed position. The upper end of the head is provided with a slot 9 through which the end of the member 4 will pass when the parts are in closed position and a lock 10 is carried by the outer end of the arm, with its outer edge in alignment with the inner wall of the slot so that the bolt 11 of the lock, when projected, will extend across the slot and will thus engage one of the openings 5 to hold the parts in closed or partly closed position. The keyhole of the lock is shown at 12. The arm is provided

with a depending projection 13 which may be adjustably connected with the arm, if desired.

The device is placed at the junction of the carburetor A and the intake manifold B, the ears 2 overlapping the outer face of the enlarged lower portion of the manifold, with the perforations aligning with the holes in the large portions of the manifold and carburetor so that the bolts *a* which connect the carburetor and manifold together will pass through the ears and thus fasten the device in place.

The arm A' of the throttle valve of the carburetor will extend over the part 1 of the device so that when the arm 6 is in its lowest position, the projection 13 will be struck by the said arm A' when it has been moved to a certain extent to open the throttle valve and thus prevent further opening movement of the valve. By partly raising the arm 6 and causing the bolt of the lock to engage the upper keeper opening 5, the projection will be raised above the throttle arm so that it will not interfere with the movement of said arm and thus the motor can be actuated the same as if the device were not in use. When the device is in fully closed position, the lower portion of the head 8 will cover one of the bolts *a* and thus prevent the detachment of the carburetor from the manifold in an attempt to remove the device.

From the foregoing, it will be seen that I have provided a lock for limiting the opening movement of the throttle valve of a motor and thereby preventing the vehicle from being driven beyond a certain speed, the device being put in place without changing any of the parts of the vehicle or its motor and when in locked position, preventing its removal by an unauthorized person. With this device, an owner of a vehicle can prevent the driver of the vehicle from driving the same at an excessive speed. By making the projection 13 adjustable, the device can be set to permit the maximum speed of the vehicle to be adjusted to any desired degree.

It is to be further understood that the right is reserved to change the construction so that it may be attached to carburetors other than those which are attached at the junction of the two flanges, either with clamps or bolts.

The device can be set to permit the maximum speed of the vehicle to be adjusted to

any desired degree, even to the extent of holding the throttle valve entirely closed so that it can be used to prevent theft.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device for preventing a motor vehicle being driven beyond a certain speed, comprising a body adapted to be held in place by the bolts which connect the carburetor with the inlet manifold, an arm hingedly connected with the body, a keeper member on the body, lock means on the arm for engaging the keeper member and a projection on the arm which is engaged by the throttle

arm of the carburetor when the device is in closed position.

2. An attachment for a vehicle comprising a base having perforated depending ears thereon adapted to receive the bolts which connect the carburetor with the intake manifold and which has a central portion placed under the arm of the throttle valve, an arm hingedly connected with the base, a keeper member on the base, a casing on the arm for receiving the keeper member when the arm is in lowered position, said casing also covering one of the bolts when the arm is in lowered position, a lock carried by the arm, the bolt of which will engage a part of the keeper member and a depending projection on the arm for limiting the movement of the throttle arm when the device is in closed position.

In testimony whereof I affix my signature.

SAMUEL CHARLES YOUNG.
